UNITED STATES PATENT OFFICE.

JAMES A. ROBB, OF SAN JOSÉ, CALIFORNIA.

FEED MECHANISM FOR LATH-SAWING MACHINES.

SPECIFICATION forming part of Letters Patent No. 288,493, dated November 18, 1883.

Application filed June 4, 1883. (No model.)

To all whom it may concern:

Be it known that I, JAMES A. ROBB, of San José, in the county of Santa Clara and State of California, have invented certain new and useful Improvements in Feed Devices of Lath-Sawing Machines; and I do hereby declare that the following is a full, clear, and exact description of the same, reference being had to the accompanying drawings.

10 My invention relates to improvements in the feed mechanism of machines for sawing out stuff for laths and like purposes, in which a set of feed-rolls advance the slab or stuff to and carry it past a gang of saws, and a set or 15 sets of pressure-rolls arranged over the feed-rolls operate to produce regular feed or progression of the material through the machine.

My improvements consist, first, in making each pressure-roller of the set self-adjusting in 20 a vertical direction, and also, in connection therewith, providing a lifting device or means by which the entire set is raised and handled together. This part of my improvement provides for an independent adjustment of each 25 pressure-roll, by which the several rolls can automatically adapt themselves to any irregularity or difference in thickness of the slab or stuff. It also enables the whole set to be raised and handled by a single bar or operating-lever when placing stuff in the machine, and at other times, as required in the work being done.

The second part of my improvement consists in a novel means of hanging and supporting the shafts that carry the pressure-rolls, whereby the weight of the rolls on one end of the shaft is counteracted and the shaft sustained and caused to move always in horizontal position or uniformly at both ends while being raised and lowered. By means of this part of my invention the shaft-boxes are relieved of irregular strain and friction, and pressure-rolls of heavy weight are easily and readily handled.

Referring to the accompanying drawings, 45 Figure 1 is an elevation of a machine to which my improvement is applied. Fig. 2 is a plan or top view of Fig. 1. Fig. 3 is a vertical section taken longitudinally through the center of the machine. Fig. 4 is a vertical cross-section taken through the center of the supporting frame and hangers that carry the independently-adjustable pressure-rolls.

A A represent the bed and frame-work, of any suitable construction to support a saw-arbor and furnish bearings for the necessary 55 shafts and other mechanism.

B is the saw-arbor, and C its driving-pulley.

D D are the shafts carrying the feed-rolls D' D'', and E E are the pulleys that drive 60 them. These shafts have bearings in boxes d d' on the frame at one side, and in similar boxes at the opposite side.

G is a pressure-roller mounted on the free outer end of a shaft, g, that is held in sliding boxes 65 h h' in the standards or guides h h''. These boxes are immediately over and in line with the feed-roller-shaft boxes d d' of shaft D. Similar guides, h h', on the opposite end of the machine-frame, beyond the saw-arbor, support a 70 box, H, within which are suspended, each independent of the other, a number of toothed or barbed pressure-rolls, I I. These rolls or toothed disks are equal in number to the saws, and they are set to bear upon the slab or thickness of stuff between the saws. The frame or box H is supported by a shaft, K, which rests in a sliding box, k', in the slot of the standard h'', and extends across the machine-frame to a 75 similar box on the other side. This shaft and its bearings are immediately over the shaft of 80 roller D''. Vertical movement of the box H is obtained through the medium of a treadle and connecting-rods and levers attached to the shaft K, by which the whole set of rolls or 85 disks I can be raised and held up. An independent movement and separate adjustment of each roll are provided, however, by which they accommodate themselves to the irregularities and unevenness of the surface of the 90 work. For this purpose the box H is a frame with ways, grooves, or guides m m, and a rod or fixed shaft, n, is carried across at the top parallel with but somewhat above the line of the lifting-shaft K. Slotted plates or slides 95 P, suspended from the shaft n, are set side by side in the guides, but sufficiently clear of one another to slide freely up and down. From these slides P hangers p p furnish bearings for the disks I. Each plate P therefore supports a 100 disk, and the whole set are suspended from the fixed shaft n across the top of the vertically-movable frame or box H. The slots l l in these plates are long enough to give consid-

erable vertical movement, and according to the capacity of the machine or the diameter of the saws employed. Independent movement of the disks is thus provided, while the whole set can be raised and held up at any time to clear the log, or to adjust them to the work when newly entered. This lifting mechanism consists of a rock-shaft, R, over which is placed a sleeve, R', having an arm, S, secured to it at one end and a similar arm, S', at the opposite end, near the saw. These two arms have forked ends *t t*, that embrace the shaft K. A rocking arm, T, is also secured to the sleeve, and its free end is connected with the inner end of a lever of the second order, V, by a pitman, *u*. The fulcrum of this lever is at *V*, and its outer end terminates in a pedal beyond the frame. Pressure upon the lever will depress the arm T and raise the box H in its guides. To lift the front pressure-roll, a similar mechanism is employed, the two pedals being brought together at the front of the machine, for convenience of the operator. This front roll is then operated by the rock-shaft R, the arms S' S', the treadle W, and the connections *w w'*. This construction of lifting mechanism is readily applied, and being always under complete control of the workman, it gives him perfect command over the pressure-rolls.

The peculiar application and arrangement of the rock-shafts R R and the arms S S S' S' preserve the horizontal position of the roller-shafts and cause them to move up and down smoothly without binding at either end in the guides. The tendency of the greater weight at the outer ends is to throw the boxes out of line and cause the shafts to lift unevenly; but this is counteracted by the arms S', and equal support is given to both ends of the shaft just inside the guides. By connecting the arms S S of each rock-shaft together, a stiff frame is produced and uniform movement insured.

This is the purpose of the brace or tie-rod *y*. (Seen in Fig. 2 of the drawings.)

Having thus fully described my invention, 45 what I claim, and desire to secure by Letters Patent, is—

1. In a lath-sawing mill or machine of like character, the combination of a feed-roll, a gang of suspended pressure-rolls, each one of 50 which has an independent self-adjusting vertical movement in vertical ways, with said vertical ways, and with mechanism, substantially as described, for lifting or dropping the whole set or gang at once, as set forth. 55

2. In a sawing-machine, the combination, with the slotted guides *h*³, of the box H, moving therein, slotted plates P, working in the boxes H, provided with the hangers *p p*, in which the rolls are suspended, rod *n*, passing through the 60 slots in the plates P, shaft K, to which the whole series of rolls I I are connected, and a rock-shaft, R, and connections, substantially as set forth, for moving the entire set of rolls, substantially as set forth. 65

3. The combination, with the pressure-roll shaft *g*, of the sliding boxes in which it is held, guides *h*², on which the boxes move, rock-shaft R, tie-rod *y*, arms S² S³, which are secured to shaft R and loosely take hold of shaft *g*, arm *w'*, 70 secured to shaft R, lever W, and connection *w*, whereby the shaft *g* is raised or lowered. 75

4. In a saw-mill or machine of the kind described, the combination of the pressure-roll shaft, and rolls suspended thereby, with a rock-shaft, as R, and connections, as S S', between the two shafts, a lever or treadle, and connections to the rock-shaft, whereby the pressure-roll shaft is depressed or elevated. 80

Witness my hand and seal.
